(57) **CLAIM**

The ornamental design for a pouch for cellular phone, as shown and described.

DESCRIPTION

FIG. 1 is a front, right side, perspective view of a pouch for cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a reference view thereof; and,

FIG. 9 is an enlarged view of the face structure of FIG. 1.

The broken line are included for the purpose of showing portions of the article and form no part of the claimed design.

1 Claim, 9 Drawing Sheets
